UNITED STATES PATENT OFFICE

ALLAN S. BARROWS, OF SAN FRANCISCO, CALIFORNIA, ASSIGNOR TO THE YOUNGSTOWN STEEL DOOR COMPANY, OF CLEVELAND, OHIO, A CORPORATION OF OHIO

CAR DOOR

Application filed August 10, 1927. Serial No. 212,004.

This invention relates to improvements in car doors.

An object of the invention is to provide a closure of the double outside sliding type for the door opening of a railway car, said closure including a main door and an auxiliary door of a character more particularly used in connection with cars in which automobiles, furniture and other large articles, are transported.

A more particular object of the invention is to provide a closure of the character referred to in which the auxiliary door carries a metallic door post having means adapted for the detachable reception of grain boards such as utilized when the cars are employed for the transportation of grain or similar material, and wherein the connection of the boards with the auxiliary door post is effected without the use of nails, bolts or other fastening devices.

A further object of the invention is to provide a double door closure of the character mentioned, wherein means are provided for automatically locking the auxiliary door in its so-called closed position so as to provide an abutment with which the main door cooperates.

Other and further objects of the invention will more clearly appear from the description and claims hereinafter following.

In the drawings forming a part of this specification, Figure 1 is a broken horizontal sectional view taken through the main and auxiliary doors, and the side door posts of a railway car, the doors being broken to better accommodate the view to the sheet. Figure 2 is a vertical sectional view of the invention taken substantially on the line 2--2 of Figure 1, and showing the mountings on the car for supporting the doors, parts of the construction being broken. And Figure 3 is a vertical sectional view corresponding to line 3--3 of Figure 1, and showing upper and lower parts of the door frame, portions of the view being broken away.

Referring to the drawings, 10 and 11 indicate portions of the side wall of a box car, and 12 and 13 denote vertically extend-

ing door posts at opposite sides of the door opening in the side wall of the car, each of the posts 12 and 13 being provided with an angular metallic cover plate indicated at 14 and 15, one end of each of the free ends 16 and 17 of the plates 14 and 15 providing means adapted to co-operate with portions of the door structure hereinafter described. The upper portion of the door frame is defined by a Z-shaped side plate indicated at 18, the depending flange of which has mounted thereon a Z-shaped member 18a having a depending flange 18b. The threshold of door frame is indicated at 19, and a track 19a is provided mounted on brackets secured to the side sill of the car.

In the arrangement shown, two sliding outside doors are employed, one of which may be termed the auxiliary door and designated A, and the other a somewhat wider door which may be termed the main door and designated by the reference character B. The auxiliary door A is composed of sheet metal throughout and preferably includes a plurality of connected panels arranged in rectangular form, the forward and rear edges of the rectangular formation being provided with vertically extending corrugations 20 and 21 which merge at the top and bottom portions of the rectangular formation with horizontally disposed corrugations 22 and 23, the rectangular formation outwardly of the corrugations 20--21 being provided with marginal portions 24 and 25, while at the top and bottom of the door marginal sections 26 and 27 are provided. At the top of the door the corrugation 23 is spanned by a reinforcing strip 28 which is riveted to the main body portion of the door as indicated at 29 and 30. On the outer surface of the marginal section 26 of the main body portion of the door along the top edge thereof, there is provided an angle bar 31 having one flange secured to said marginal section by the rivets indicated at 30, while the other flange of the bar 31 is horizontally disposed and is adapted to cooperate with the depending flange of the Z member 18a to maintain the door in proper position during its sliding movements. At

the bottom of the door the corrugation 22 is spanned by reinforcing strip 32, said strip being fastened to the main body portion of the door by rivets indicated at 33 and 34. 5 Secured to the outer side of the marginal section 27 at the lower edge of the door, are roller housings, indicated at 35 carrying rollers 36 which run upon the track 19a. At 10 the rear of the door the corrugation 20 is spanned by reinforcing strip 37 secured to the main body portion of the door by rivets 38, the strip 37 at the extreme marginal edge of the door being provided with an angular extension 39 adapted to cooperate with the 15 extension 16 on the plate 14 to provide a weather and spark seal at the rear end of the door when the same is in closed position. The corrugation 21 at the forward edge of the door is also spanned by a reinforcing 20 strip 40, said strip having its opposite marginal edges secured to the main body portion of the door by rivets 41 and 42. To the outer surface of the marginal section 25 is secured the movable door post 43. The post 25 43 comprises a relatively heavy metallic member including a web 44 extending substantially perpendicular with respect to the main plane of the door, and at each end of the web 44 the member 43 is provided with 30 angularly disposed head portions 45 and 46, the portion 45 providing flanges 46a and 47, while the head portion 46 provides flanges 48 and 49. The flange 48 of the head 46 of the member 43 is disposed with its inner 35 surface flat against the marginal surface of the door A and the flange 48 is rigidly secured to the marginal section by the rivets 42. The web 44 of the member 43 is of such length as to project inwardly of the main 40 plane of the door A a considerable distance so as to dispose the head 45 of the member 43 somewhat inwardly of the plane defined by the inner face of the door post 12. Extending diagonally from the inner surface of 45 the door A toward the web 44 of the member 43 is a reinforcing element 50. Said element is secured to the door A by the rivets 41, and to the web 44 by the rivets indicated at 51. Inwardly beyond the connecting rivets 51 the element 50 is provided with 50 an angular flange 52 spaced from and disposed substantially in parallel relation with the flange 46a of the head 45 of the member 43, the flanges 52 and 46a and the web 44 defining a groove 53 adapted for the detachable reception of the ends of the boards 54, the opposite ends of the boards 54, when the door A is in closed position, being nailed to the post 12 as indicated at 55. Secured 55 to the surface of the web 44 opposite to the face to which the element 50 is secured is a member 56 channel-shaped in cross section, the web of said member being secured to the web 44 of the post 43 by means of the 60 rivets 51 which secure the element 50 in position, and by the rivets 57 which extend through the web of the channel member and the web of the post 43. The flange 57a of the member 56 is disposed in spaced parallel relation with the flange 47 of the member 43 to provide a groove 58 for the reception of the ends of the boards 59, the opposite ends of said boards being adapted to be nailed to the post 13 as indicated at 60. The other flange 61 of the member 56 is disposed in spaced relation with reference to the flange 49 of the head 46 of the member 43 and provides a groove 621 for the reception of the forward edge of the main door B. The main door B is also composed throughout of metal, and except for its greater width, and the omission of the door post, is practically identical in construction with the auxiliary door A and similar reference characters will be utilized to designate like parts of both. 70

In the use of doors of this character, means must be provided for locking the auxiliary door A in closed position. In effecting this purpose, a gravity actuated latch 62 is provided. Said latch is pivotally mounted upon a bracket 63 secured to the web of the Z-shaped member 18, by means of a pivot pin 64, to swing in a plane parallel to the plane of movement of the door A 95 when slid back and forth across the door opening. The end 65 of the latch 62 is of greater length than the end 66 of said latch so that the end 65, which is disposed in a direction toward the door A, is normally urged, through the influence of gravity, in a downward direction, the upper edge of said latch being bevelled as indicated at 67 to permit the end 65 to be moved in an upward direction, while the extremity 68 of the end 66 of the latch bears against the under-surface of the web of the member 18 to limit downward movement of the end 65 of the latch. The end 65 of the latch is provided with a shoulder 69 adapted to engage 100 behind the top end of the web 44 of the door post 43 when the door A is moved in a closing direction, the end 65 of the latch being bevelled as indicated at 70 to permit the latch to ride over the top of the web 44 of the post 43 during the time that the door A is being closed. The end 65 of the latch 62 is also provided with a shoulder 690 adapted to engage the top end of the web 44 in certain positions of the parts. Reciprocably mounted upon the inner face of the web 44 is a locking bar or bolt 71, said bar being provided with slots 72 adapted to receive rivets 73 which extend through the web 44 of the member 43, and the web 110 of the member 56, whereby the bar 71 may be reciprocated in a vertical direction, the lower end 74 of which under the influence of gravity normally projects below the bottom edge of the door post and is adapted to 115

120

125

130

135

be disposed in a recess 75, corresponding in position to the shoulder 69, formed in a keeper casting 76. Said keeper casting is also provided with a recess 750, corresponding in position with the shoulder 690, adapted for the reception of the lower end of the bar 71 when the parts are in certain positions. The casting 76 is mounted upon the threshold 19 of the door and is provided with inclined surfaces 77 and 78, the surface 77 providing cam means to permit the lower end 74 of the bar to ride thereover into position to enter the recess 75 when the door is being moved to closed position. The upper end of the bar 71 is provided with a turned portion 79 adapted to engage the lower surface of the end 65 of the latch 62 so that upward reciprocation of the bar 71 will move the end 65 of the latch so that the shoulder 69 is clear of the web 44, the upward movement of the bar 71 also serving to retract the lower end 74 of the bar from the recess 75 in the keeper casting. The reciprocation of the bar 71 may be effected through the medium of a handle 80 which projects outwardly through a slot 81 in the diagonal member 50, movement of said handle in an upward direction serving to lift the bar 71.

When it is desired to use the car for the transportation of large objects, such as automobiles, furniture, and the like, the boards 54 and 59 of course are dispensed with. During such use the auxiliary door A when moved in a closing direction automatically brings into operation the locking bar 71 and the latch 62, the lower end of the bar dropping into the recess 75 in the casting, and the shoulder 69 of the latch dropping over the upper end of the web 44 of the post 43, thereby securing the auxiliary door in its closed position, the post member 43 serving as an abutment and seal for the door B when the latter is closed, the forward edge of the door B being accommodated in the groove provided by the flanges 61 and 49 of the channel member 56 and head 46 of the post 43. If it is desired to move and lock the door A a slightly greater distance forwardly as is sometimes necessary on account of distortion of the car body and other parts, the lower end of the bar 71 may be retracted and engaged with the recess 750 which brings the shoulder 690 of the latch 62 into position to engage the top end of the web 44. In order to open the doors, the main door B is first slid back in the usual manner, after which the handle 80 may be grasped by the operator and lifted, which retracts the lower end of the bar 74 from the recess 75 or recess 750 as the case may be to free the lower end of the door post, and by reason of the simultaneous upward movement of the angular portion 79 of the bar, the latch 62 is lifted, freeing the upper

end of the door post from the shoulder 69 or 690, thereby permitting the door A to be slid in an opening direction.

When the car is used to transport grain or similar commodities, and no necessity is present for the use of the large door opening, the auxiliary door A may be moved forwardly and locked by the bar 71 and latch 62 in either of two positions as above described. The ends of the boards 54 may then be inserted into the groove 53 provided by the flange 46^a and 52 of the members 50 and 45, and the opposite ends of the boards may be nailed to the door post 12. In like manner the ends of the boards 59 may be inserted into the groove 58 provided by the flanges 47 and 57, and the opposite ends of the boards nailed to the post 13. The main door B then may be closed and locked.

By the above described arrangement it will be appreciated that automatic means are provided for locking the door both at its upper and lower ends which means may be simultaneously disconnected to permit opening movement of the door. In addition, the door post is of such character as to permit of the engagement of the grain boards therewith without the necessity of nailing or bolting the same to the movable door post, and hence said door post is of practically indestructible character and provides for efficient and convenient operation at all times.

While I have herein shown and described what I consider the preferred manner of carrying out the invention, the same is merely illustrative and I contemplate all changes and modifications which come within the scope of the claims appended hereto.

I claim:

1. In a car, the combination with a main sliding door; of an auxiliary sliding door having the main portion comprised of sheet metal terminating in a marginal flange, the latter having a member associated therewith, said member comprising a web portion extending inwardly of the main plane defined by the body portion of said door, and substantially at right angles thereto, and provided with oppositely extending flanges, one of which is rigidly secured to the forward edge of said auxiliary door on the outer face thereof, whereby said web portion provides an abutment and the rigidly secured flange protects the sheet metal flange.

2. In a car, the combination with a main sliding door having a thin forward edge; of an auxiliary sheet metal door having a movable door post associated with its front edge, said door post comprising a web portion extending inwardly of the plane defined by the main body portion of the door and substantially at right angles thereto, said web portion being provided with

flanges extending laterally to opposite sides of said web portion, one of which is adapted to overlap the within edge of said main door on the outer face thereof when the latter is closed, and the other of which is rigidly secured to the forward edge of said auxiliary door on the outer face of the latter, said web portion and rigidly secured flange protecting the forward edge of the sheet metal of the auxiliary door.

3. In a car, the combination with a main sliding door; of an auxiliary sliding door, said latter door having a member associated with its forward edge, said member comprising a portion extending inwardly of the plane defined by the main body portion of the door, and substantially at right angles thereto, and including oppositely disposed flanges upon its outer end, one of which is rigidly secured to the outer face of the marginal edge of said auxiliary door, while the other is adapted to cooperate with the forward edge of the main door when the latter is in closed position; and means associated with said member and having a portion inwardly spaced from and extending substantially parallel with said other flange of said member to provide a groove for the reception of the forward edge of the main door.

30 4. In a car, the combination with a main sliding door; of an auxiliary sliding door having rigidly secured at its forward edge a member including a web portion extending inwardly beyond the plane defined by the main body portion of said door and substantially at right angles thereto said web portion providing an abutment for the forward edge of the main door, the inner end of said member having laterally disposed flanges connected thereto; and means connected with said web portion at opposite sides thereof and arranged in spaced relation with reference to said laterally disposed flanges and cooperating with the latter to provide recesses for the detachable reception of ends of boards.

5. In a car, the combination with a main sliding door; of an auxiliary sliding door, the latter having rigidly secured to its forward edge a member provided with a web portion extending inwardly of the plane defined by the main body portion of the door, said web portion forming an abutment for the front edge of the main door and at its outer end being provided with a flange adapted to overlap said main door when the same is closed, and said portion at its opposite end being provided with lateral flanges extending to opposite sides of said portion; and means disposed between the ends of said portion and cooperating with the laterally extending flanges thereon to provide recesses for the detachable reception of the ends of boards.

6. In a car, the combination with a main

sliding door; of an auxiliary sliding door, the latter having rigidly secured to its forward edge a member provided with a portion extending inwardly of the plane defined by the main body portion of the door, said portion at its outer end being provided with a flange adapted to overlap said main door when the same is closed, and said portion at its opposite end being provided with flanges extending to opposite sides of said portion; and means disposed between the ends of said portion and cooperating with the last mentioned flanges thereon to provide recesses for the detachable reception of the ends of boards, said means also cooperating with the flange at the outer end of said portion to provide a recess for the reception of the forward edge of said main door.

7. In a car, the combination with a main sliding door; of an auxiliary sliding door; a member secured to the forward edge of said auxiliary door and extending inwardly of the main plane thereof and arranged to serve as an abutment for the forward edge of the main door; and means adjacent the inner end of said member on opposite sides thereof having elements adapted for the loose accommodation of oppositely extending board ends.

8. A door of the character described, comprising a main body portion, and a door post secured along one edge, said post including a portion extending to one side of the main plane of the door and provided with an angularly disposed flange at its inner end; and means secured to said door and to said portion, said means cooperating with said flange to provide for the detachable reception of a board end.

9. A door comprising a main body portion and a door post secured at one edge thereof, said post including a portion extending substantially at right angles to the main plane of said door and inwardly thereof, the opposite ends of said portion being provided with angularly disposed flanges; and a member secured to said portion having means cooperating with the flange at the inner end of said portion adapted for the detachable reception of a board end, and the opposite end of said member having means cooperating with the flange at the outer end of said portion to provide a recess for the detachable reception of the edge of a cooperating door.

10. In a car, the combination with a main sliding door composed of sheet metal; of an auxiliary door having a member disposed at its front edge, said member including a portion extending inwardly of the plane defined by the main body of the door, said portion at its outer end being provided with flanges extending laterally upon each side of said portion, one of which is rigidly secured to the edge of said auxiliary door;

- and a bracing element secured to said door in its main plane and extending at an angle inwardly toward said member and being secured thereto, said portion being provided 5 with an angular flange on its inner end, and said element being provided with a flange on its inner end, said flanges being spaced apart to provide a recess for the detachable reception of a board end.
- 10 11. In a car, the combination with a main sliding door; of an auxiliary sliding door having a member secured to its forward edge, a portion of said member extending to one side of the main plane of the door, 15 and said portion being provided at one end with oppositely extending laterally disposed flanges, and at its opposite end being provided with similar flanges; means mounted on said member at opposite sides thereof 20 and having portions co-operating with the inner flanges on said member to provide recesses for the reception of board ends, said means on one side of said member co-operating with one of the flanges on the outer 25 end of said member to provide a recess for the reception of the forward edge of said main sliding door.

12. A door comprising a main portion, a post attached to one edge thereof and extending at an angle to the main plane of 30 said portion; bracing means attached to said main portion and extending diagonally to and secured to said post and thereby forming a pocket between the post bracing 35 means and main portion; and latching means housed within said pocket.

13. In a car, the combination with a slideable auxiliary door; of a post secured to the front edge of said door, said post being 40 provided with three longitudinally extending grooves, two of said grooves being located at the inner end of said post and adapted for the reception of ends of grain boards, the third groove being disposed at 45 the outer end of the post and adapted for the reception of the forward edge of a main door.

14. In car construction, the combination with a door frame member; of a slideable 50 door having a post at its forward edge; and cooperable means mounted on said post and frame member having different positions of interlocking engagement whereby to lock the door in a plurality of different positions 55 whereby to compensate for variations in the car structure.

15. In car construction, the combination with a car body having a door opening defined in part by a threshold and a lintel; of 60 a door slideable over said opening and provided with a post at its forward edge; cooperable means carried by the lintel and the upper end of said post adapted for interlocking engagement in a plurality of 65 positions; and cooperable means carried by

the post and the threshold adapted for interlocking engagement in a plurality of different positions whereby to compensate for variations in the car structure.

16. In a door, the combination with a main 70 portion comprised of sheet metal having strengthening indentations therein, the forward edge of said door terminating in a marginal flange in the general main plane of the sheet metal; of a rolled section post 75 having web and flange sections, the flange section being secured to the outer face of said marginal flange of the sheet metal portion, the web section of said post extending inwardly of the main plane of the door; and a diagonally disposed brace plate secured 80 along its edges to the main sheet metal portion and the inwardly extended web section of the post, respectively, said brace plate extending substantially from top to bottom 85 of the door.

17. A door for railway cars comprising: A sheet metal main portion having a flat marginal flange at its forward edge in the same plane as the main portion of the sheet 90 metal; an I-beam having one of its flanges overlapped and secured to said marginal flange to weather protect the latter, the corresponding adjacent flange of the I-beam 95 extending in the opposite direction and adapted to overlap the forward edge of an adjacent door; and bracing means extending diagonally from the main sheet metal portion of said door inwardly and forwardly to and secured to the web of said I-beam. 100

18. As an article of manufacture, a slideable metal door having a metal sheet with a vertical corrugation at the front edge thereof offset outwardly from the main plane of the sheet and provided with a flat 105 marginal portion beyond the corrugation; a post having a web section and a flange section along its outer edge, the flange section being secured to the outer face of said flat marginal portion, the web section extending inwardly of said main plane of the sheet; and a vertically extending post bracing plate attached to the metal sheet inwardly of said corrugation and extending 110 diagonally to and secured at intervals to the web section of said post inwardly of the plane of the sheet, said bracing plate being in spaced relation to said marginal portion.

19. In a car having a door opening, the combination with a main slideable door; of 115 an auxiliary slideable door, said auxiliary door having a hollow tubular combined post and bracing structure along the forward edge thereof; means for latching said post and bracing means to the car body when the auxiliary door is in closed position; and means for releasing said latching means, the releasing means including an element housed within said tubular post and bracing structure. 120 125 130

20. As an article of manufacture, a slide-
able metal door having the main portion
thereof comprised of a metal sheet with a
vertically extending corrugation adjacent
5 the front edge thereof and provided with a
flat marginal portion beyond said corruga-
tion; a bridging strip extending lengthwise
of said corrugation and overlying the same
and secured along its edges to the metal
10 sheet along opposite sides of said corruga-
tion; a post having a web section and a
flange section extending vertically along its
outer edge, said flange section overlying the
outer face of said marginal portion, the web
15 section extending inwardly across the edges
of both said marginal portion and bridging
strip to a point inwardly of the main plane
of the sheet; and a vertically extending brac-
ing plate attached to the metal sheet in-
20 wardly of said corrugation and to the web
section of said post, said bracing plate ex-
tending angularly inwardly from the main
plane of the sheet.

In witness that I claim the foregoing I
25 have hereunto subscribed my name this 27th
day of July, 1927.
